UNITED STATES PATENT OFFICE.

CHARLES B. WEBSTER, OF FALL RIVER, MASSACHUSETTS, ASSIGNOR TO JAMES K. LANNING, OF FALL RIVER, MASSACHUSETTS.

HALF LAP FOR COMBS.

Application filed July 28, 1924. Serial No. 728,563.

This invention relates to half-laps which are used in combing machines employed for combing out the short staple lint in the preparation of textile fibres for the manufacture of yarn, and is intended to provide a simple and reliable construction for effectively performing the combing operation while facilitating the assemblage and replacement of the individual comb bars.

Heretofore it has been the practice to use half-laps in which a number of separate bars, attached to the base member of the half-lap, were each provided with needle-carrying bars, the comb bars being held in place usually by screws inserted through the body of the base from the inside outwardly into engagement with the threaded holes formed on the inside faces of the comb bars, space being left between the bars for the intervening needle bars which carry the rows of needles that perform the combing operation as the half-lap is revolved. This construction and arrangement results in leaving cracks or interstices, of greater or less size, in which the lint rapidly accumulates as it is not effectively removed by the clearing brushes, and in consequence the combing operation is more or less imperfectly performed.

The present invention is characterized by a base member whose outer surface is cylindrically curved from front to rear, and having abutments or ledges located at its front and rear edge portions between which abutments a series of comb bars is secured by means of a detachable connection which permits the comb bars to be applied one after the other, means being provided for forcing the properly shaped comb bars tightly together and for maintaining them in their fixed operative position. The comb bars themselves are constructed so that their adjacent faces fit snugly against each other without leaving interstitial spaces, and are formed to interlockingly engage retaining means carried by the base member and have their outer or peripheral faces so disposed or sloped that the rear edge portion of each comb-bar is inwardly offset below the level of the relatively higher forward edge portion to which the needles are applied or, in other words, so that the adjacent edges of two adjacent comb-bars are located at different radial distances from the axis of revolution of the half-lap in order to

allow the clearing brushes to more effectively keep the needles clear of lint.

These and other features of the invention will be more particularly explained in the following specification and will be defined in the claims hereto annexed.

In the accompanying drawings I have illustrated a simple and convenient form of construction and arrangement embodying the principles of this invention, in which:

Figure 1 is an end elevation of my improved half-lap as applied to the supporting shaft which is shown in section.

Figure 2 is a longitudinal section through the half-lap on the irregular plane indicated by section line α — α , Figure 1.

Figure 3 is a detail view showing, in rear elevation, the wedge member by which the separate comb-bars are tightly forced together and held in operative position for combing.

Figure 4 is an end elevation of a portion of a half-lap showing a modified form of comb-bar fastening means.

The half-lap herein shown comprises a base member or body 2, of general arcuate shape, comprising a segment of a cylinder with forward and rearward attaching extensions or flanges 3 through which are passed the attaching screws which fasten it to the rotary supporting shaft 1, by which it is revolved to bring the combing needles in contact with the film of fibres to be combed out. The base member, at its front end, is provided with a projecting ledge 6, and at its rear edge or side with another somewhat similar abutment or ledge 5, which two ledges bound the circumferential surface to which the comb-bars are applied.

The base member 2 is also provided around its circumferential or outer face with comb-engaging and attaching members which, in this case, are shown as comprising flanged L-shaped ribs 2^a arranged at the opposite ends of the base member, and an intermediate flange or rib 2^b formed with an overhanging flange or portion, and these attaching ribs or tongues form, so to speak, retaining tracks on which the comb-bars are placed one after another somewhat after the fashion of beads on a string.

The comb-bars themselves comprise longitudinal bars 7 of a thickness to space the rows of needles the required distance apart, and are formed near their inside edges with

transverse grooves or L-shaped cuts machined to exactly fit over the attaching members 2^a, 2^b, with their bottom or inner edges resting against the peripheral face of the 5 base member. A row of properly spaced and gaged needles 8 is inserted in a longitudinal recess formed in the outer portion of the front or side face of each bar so dimensioned as to exactly receive the needles 10 and the attaching solder applied thereto in order that when the bars are assembled together, as shown in Figure 1, there may be left no crack or space for the lodgement of lint. Furthermore, the peripheral or outer 15 face of each bar is sloped inwardly or cut away so that, in assembled position, the rear portion of its peripheral surface lies nearer to the axis of rotation than its forward portion adjacent to the needles. This leaves 20 the peripheral surface of each comb-bar, immediately in advance of each row of needles, inwardly offset in relation to the peripheral surface, that is, immediately behind each 25 row of needles, the object of such offset or recessing immediately in front of each row of needles being to insure the more effective clearing away of the lint by the clearing brush which, as is well known in the art, is set to brush off the needles when the needles 30 are revolving through the lower part of their orbital course.

To insure the close arrangement or assemblage of the comb-bars and their maintenance in operative relation, while still rendering them detachable, I employ a wedge member 9 which is shaped to be inserted between the rearmost comb-bar 7 and the rear abutment or ledge 5, which is integral with the half-lap to receive the thrust of set 40 screws 10 which hold them in place. In order to exert an inward thrust on this wedge or fastening member the rear face thereof is notched to provide an inclined face 9^a in position to be engaged by the set screws 10.

In Figure 4 I have shown a modified arrangement of the fastening screw in which the wedge 11 is provided with counter-bored recesses in its peripheral face to receive the 50 head of attaching screws 12 which pass through the wedge-block in an approximately radial direction, and may be tightened to draw the wedge in place by the thrust of the shoulder formed by the head 55 instead of the thrust of the inner end of the set screw, as in the form shown in Figure 1.

When the comb-bars are assembled in the manner above described, the half-lap presents the appearance, viewed from the outside, of a solid matrix with tightly inserted needle bars. As the comb-bars differ somewhat as to the gage and pitch or inclination of the needles each comb-bar may have its designating numeral or letter to indicate its 60 proper order of arrangement in the series,

and in case of accident or injury to one or more comb-bars, the removal of the wedge permits the rearward bars of the series to be quickly withdrawn to permit the removal of the injured comb-bar and the substitution 70 of a corresponding one in its place.

Moreover, when coarser needles are used on the forward comb-bars than on the rearward comb-bars, any slight variations in the thickness of the comb-bar structure, including the needles, that results from this or from any other cause does not result in leaving any crevice or crack for the lodgement of lint since the comb-bars are forced into close contact with one another irrespective of such variations in lateral thickness. In any case, therefore, there is presented, in a properly assembled half-lap, an outer surface between the needles free from any 80 cracks tending to hold the fine lint. 85

What I claim is:

1. In a half-lap for a combing machine, the combination with a base member provided with arcuate retaining and guiding members, a series of comb-bars formed to have a circumferentially slidable retaining connection with said retaining and guiding members on said base, and means for forcing said comb-bars tightly against one another and retaining them in fixed operative relationship, substantially as described. 95

2. A half-lap for a combing machine embracing in combination an arcuate base provided at its forward and rear edge portions with fixed abutments, a series of comb-bars having interlocking circumferentially slidable connection with the base member, and a wedge adapted to be interposed between the rearmost comb-bar and the rearward abutment to force the comb-bars into firm 100 engagement with one another and retain them in fixed operative relation, substantially as described. 105

3. A half-lap for a combing machine embracing in combination a base member provided at opposite sides of its curved outer face with projecting abutments, a series of comb-bars shaped to lie closely against one another without leaving intervening cracks, said comb-bars having tongue and groove 110 connection with said base to permit them to be connected therewith and pushed circumferentially over the base member one after another to properly position them for the combing operation, means for forcing said comb-bars tightly against one another to maintain them securely but detachably in fixed operative relationship, substantially as described. 115

4. In a half-lap for a combing machine, the combination with a supporting base formed with an outer cylindrical face between front and rear abutments, a series of separate comb-bars formed to be secured to said base by an interlocking connection per- 120 125 130

mitting one after another to be shifted circumferentially over the outer face of the base to its proper operative position, each comb-bar having that portion of its exterior face adjacent to its rear edge inwardly offset with relation to the level of the forward edge of the next following comb-bar to secure more effective cleaning out of the lint from the comb by the clearing brushes, substantially 10 as described.

5. In a half-lap for combing fibres, the combination of a base member provided exteriorly with attaching means circumferentially curved to support the comb-bars, a 15 circumferential series of longitudinal comb-bars mounted exteriorly on said base in interlocked engagement with said attaching means, and means for forcing said comb-bars into close lateral engagement one with 20 another to avoid intervening crevices and for retaining them when so engaged upon said base, substantially as described.

6. In a half-lap for combing fibres, the combination of a circumferentially curved 25 base adapted to be secured to a rotary shaft, a series of circumferentially arranged comb-bars rigidly secured to said base by attaching means which permits the comb-bars to be shifted circumferentially of the 30 base until they are brought into close lateral contact one with another, whereby the absence of external crevices for the lodgement 35 of lint is obtained, substantially as described.

7. A half-lap for combing fibres embracing in combination a circumferentially curved base member, a series of parallel comb-bars secured to said base in a circumferential arrangement by tongue and groove 40 connection with said base permitting them to be shifted circumferentially of the base, and a longitudinal member arranged to force the comb-bars into close lateral engagement one with another and to retain them in such engagement, substantially as 45 described.

8. A half-lap for combing fibres embracing in its construction an arcuate base member provided on its front and rear edges with longitudinal ledges, circumferential

ribs located exteriorly of said base member, 50 a series of comb-bars transversely notched to form interlocking engagement with said ribs, an anchoring member interposed between the rearmost comb-bar and the rearward ledge, and set screws having threaded 55 engagement with said anchoring member to cause said anchoring member to force the comb-bars tightly together and hold them against displacement, substantially as described. 60

9. A half-lap for combing fibres embracing an arcuate base, a circumferentially disposed series of comb-bars each carrying a row of needles inserted in a longitudinal recess along one lateral face to lie flush with 65 said face, and means for holding each comb-bar in close lateral contact with the intervening rows of needles closely embraced between the adjacent faces of adjacent bars to avoid leaving intervening cracks for the 70 lodgement of lint, substantially as described.

10. A comb element for a half-lap embracing a longitudinal bar having a transverse thickness enabling it to serve as a spacing member between successive rows of 75 needles supported by it, and a row of transversely disposed needles secured along one side face of said bar with their tapered points projecting upward beyond the outside face of said bar, substantially as described. 80

11. A comb element for a half-lap embracing a longitudinal bar having a lateral recess extending lengthwise thereof and inwardly from its outer surface, a row of 85 transversely disposed needles secured in said recess with the exposed faces of their butt portions flush with the adjacent exposed lateral face of the bar, said bar serving as a spacing element between the two rows of 90 needles and being provided with transverse rib-receiving grooves and retaining ribs on the base of the half-lap arranged to form 95 slideable interlocking engagement with said grooves, substantially as described.

In witness whereof, I have subscribed the above specification.

CHARLES B. WEBSTER.
